(57) **CLAIM**

The ornamental design for a combined container lid and measuring spoon, as shown and described.

DESCRIPTION

FIG. 1 is a bottom front left side perspective view of a combined container lid and measuring spoon, showing my new design;

FIG. 2 is a left side view thereof, the right side view being a mirror image; and,

FIG. 3 is a front view thereof.

The broken lines in the drawings represent unclaimed subject matter and form no part of the claim.
